UNITED STATES PATENT OFFICE.

JOHN F. O'CONNOR, OF CHICAGO, ILLINOIS, ASSIGNOR TO WILLIAM H. MINER, OF CHICAGO, ILLINOIS.

BUFFING MECHANISM.

1,139,709.

Specification of Letters Patent. Patented May 18, 1915.

Application filed February 28, 1914. Serial No. 821,667.

To all whom it may concern:

Be it known that I, JOHN F. O'CONNOR, a citizen of the United States, residing in Chicago, in the county of Cook and State 5 of Illinois, have invented a new and useful Improvement in Buffing Mechanism, of which the following is a specification.

This invention relates to improvements in buffing mechanism.

10 An object of the invention is to provide a buffing mechanism for railway passenger cars and other vehicles having a preliminary spring action and a final combined spring and frictional action, the preliminary compression spring also acting simultaneously 15 with the frictional resisting mechanism.

Other objects of the invention are to provide a buffing mechanism in which two sets of combined springs and frictional shock 20 absorbing devices are twin arranged; in which the twin friction shells are made separate and detachable and in which the capacity of the buffing mechanism is very high.

The invention furthermore consists in the 25 improvements in the parts and devices and in the novel combinations of the parts and devices herein shown, described or claimed.

In the drawing forming a part of this 30 specification, Figure 1 is a horizontal, sectional view of a buffing mechanism embodying my improvements and Figs. 2 and 3 are vertical, sectional views taken respectively on the lines 2—2 and 3—3 of Fig. 1.

In said drawing, the buffing mechanism is 35 shown as comprising a rear plate 10 which abuts across sill or any other fixed part 11 of the car underframe. Mounted on the plate 10 in twin arrangement are two cylindrical, combined friction shells and spring

40 casings 12, each of which is detachable with respect to the plate 10 and centered in position thereon by means of bosses 13 formed integral with said plate. Within each combined shell and casing 12 are mounted a 45 plurality of circularly arranged friction shoes 14, a wedge or spreader 15, nested main springs 16 and a retaining bolt or rod 17, the latter extending through the wedge 15 at the inner end. Telescoped on the friction shells 12, 12 is a casing 18 having two cylindrical portions 19 united by a central web 20, the latter being slotted, as at 21, to receive a key 22 therethrough, which key 50 engages shoulders 23 formed on the inner sides of the friction shells 12, the key 22

preventing the separation of the member 18 and the shells 12 which would otherwise occur because of the springs 24 which are placed around the shells 12 and engage the rear ends 25 of the member 18. At its front 60 end, the member 18 is provided with forwardly extending triangular shaped portions 26 connected by a bridge portion 27 against which the rear end 28 of the buffer stem is adapted to press to operate the buffing mechanism. The key 22 is prevented from falling out by cotters 29, 29.

From the preceding description it will be seen that during the first part of the operation of the buffing mechanism, the preliminary compression springs 24 resist inward movement of the member 18. After the latter has been moved sufficiently for the same to engage the outer ends of the 70 wedges 15, the twin arranged friction shock 75 absorbing devices are brought into play, and at the same time it will be noted that the springs 24 assist the friction shock absorbing devices in dissipating the shock. By forming the combined shells and casing 12 80 separately and detachable, the same may be easily renewed or repaired and injury to one does not necessitate replacement of the other, thus minimizing the cost of renewals 85 and repairs.

Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

I claim:

1. A buffing mechanism including, in combination: two sets of twin arranged telescoped casings; springs normally tending to separate said casings; and a key in engagement with all of said casings and preventing separation thereof, substantially as specified.

2. In a shock absorbing device of the character described, in combination: a plate having a pair of integral bosses formed thereon; twin arranged combined friction shells and spring casings mounted on said plate, each of said combined shells and casings having a perforated inner end fitting over one of said bosses; springs and friction

- mechanism within each of said friction shells and casings; a connecting bolt extending through each friction mechanism and the corresponding boss; and a member 5 for engaging and operating said friction mechanism, substantially as specified.
3. In a device of the character described, in combination: a pair of separable friction shells arranged in twin; friction mechanism 10 and springs within each of said shells; and a member telescoped over both of said shells, said member having twin arranged portions corresponding in shape and size to the shape and size of the shells and thereby assisting 15 in maintaining said shell in proper position, substantially as specified.

4. A buffing mechanism including in combination: twin arranged friction shells; friction devices and springs within each of said shells; a member having two integral cylindrical portions arranged in twin and telescoping over the ends of said casings; and detachable means for preventing accidental separation of said member from said shells, substantially as specified. 20 25

Signed at Chicago, Illinois, this 26 day of February, 1914, in the presence of two subscribing witnesses.

JOHN F. O'CONNOR.
